United States Patent

Des. 238,902
Patented Feb. 17, 1976

238,902

MOTION PICTURE CAMERA OR SIMILAR ARTICLE

Peter Hartwein, Schwalbach, Germany, assignor to Braun
Aktiengesellschaft, Frankfurt, am Main, Germany

Filed Feb. 22, 1974, Ser. No. 445,297

Claims priority, application Germany Sept. 2, 1973

Term of patent 14 years

Int. Cl. D16—01

U.S. Cl. D61—1 B

Fig. 3

Fig. 4

Fig. 6

FIG. 5

FIG. 7

FIG. 8

FIG. 1 is a perspective view of a motion picture camera or similar article showing my new design;

FIG. 2 is a right side elevational view thereof, showing the shoulder support in raised, inactive position;

FIG. 3 is a left side elevational view thereof; in lowered, active position as in FIG. 1;

FIG. 4 is a front elevational view thereof;

FIG. 5 is a right side elevational view thereof;

FIG. 6 is a rear elevational view thereof;

FIG. 7 is a top plan view thereof; and

FIG. 8 is a bottom plan view thereof.

I claim:

The ornamental design for a motion picture camera or similar article, substantially as shown and described.
